UNITED STATES PATENT OFFICE.

ADA GARDANIER, OF CHICAGO, ILLINOIS.

DESIGN FOR A DARNER.

SPECIFICATION forming part of Design No. 34,235, dated March 19, 1901.

Application filed February 23, 1901. Serial No. 48,624. Term of patent 14 years.

To all whom it may concern:

Be it known that I, ADA GARDANIER, a citizen of the United States, residing at Chicago, in the county of Cook and State of Illinois, have invented and produced a new and original Design for Darners; and I do hereby declare the following to be a full, clear, and exact description of the same, reference being had to the accompanying drawings, forming a part thereof.

In the accompanying drawings, Figure 1 is a perspective view of a darning embodying my design and looking at the same from above. Fig. 2 is a similar view looking at the darning from beneath, and Fig. 3 is a side elevation of the same.

The leading feature of my design for a darning consists of a main body portion having an upwardly-curved top surface and a flat bottom or under surface with rounded corners and substantially square at one end and tapering to a point at its other end.

1 in the drawings represents the upper surface of the darning, which is curved upwardly and is broader at its end 2 than at its end 3. 25 The under side of the darning is flat, as at 4, and tapers from its heel to its toe end, as shown in Fig. 3, which makes the darning much thicker at said heel end than at the toe end. 30

The darning is provided with a groove 5, extending all around the same.

Having now described my design, what I claim as new, and desire to secure by Letters Patent, is—

35 The design for a darning, substantially as herein shown and described.

In testimony whereof I hereunto affix my signature in presence of two witnesses.

ADA GARDANIER.
